Primary Examiner — Eric Goodman*Assistant Examiner* — Luqman McNeil(57) **CLAIM**

I claim the ornamental design for the walking cane with lights integrated therein, as shown and described.

DESCRIPTION

FIG. 1 is a front view of the walking cane with lights integrated therein.

FIG. 2 is a rear view of the claimed design.

FIG. 3 is a left side view of the claimed design.

FIG. 4 is a top view of the claimed design.

FIG. 5 is a bottom view of the claimed design; and,

FIG. 6 is a perspective view of the claimed design.

1 Claim, 3 Drawing Sheets(56)
